Letters Patent

The schedule referred to in these Letters Patent, and making part of this same, containing a description in the words of the said Henry Allor himself, of his improvement in the mowing machine.

To all to whom these Presents shall come.

Be it known, that I, Henry Allor in the county of Lincoln and state of Tennessee have invented a new and useful mowing Machine, and that the following is a full and exact description thereof. I have two wheels five feet in diameter, and a axle from six to eight feet long, the first or machinery wheel, has a cast iron cog wheel, four feet in diameter, attached to it which works a pinion of fourteen inches in diameter on an iron shaft, to which is attached another cog-wheel of cast iron, three feet in diameter. This wheel turns another pinion on an iron shaft with a crank at one end of the iron shaft, fourteen inches in length, to this shaft is attached a cast iron fly-wheel, three feet in diameter, and sufficiently heavy to over come the dead points of the crank. This machinery determines the length of the frame from the shaft back, which is made of three strong seasoned scantling four by ten inches and confined to the axle by screw bolts in the following manner. The first runs on the outside of the machinery wheel, having a clamp which rests on the point of the axle, the second as near the inside of the wheel which is six inches in the tread, as to admit the machinery in a compact form, the third or last piece is twelve inches in the clear from the second piece, between these pieces, and immediately before the axle, there is an upright axle passing thro' a sliding frame, hoisted and lowered as to work with ease. This sliding frame moves through a space equal to double the length of the crank by a pulley, connected with the crank and frame in thin iron slides, swaged fast to the frame timbers, similar to the teakhead of an engine.

In a upright frame, connected to the sliding frame, confines the top of this axle by a small yoke iron, between the sliding and upright frame. There is a semi circular cog wheel of cast iron, the circumference of which, corresponds with the length of the slide and works in a notch, thereby turning the upright shaft in it's round, backwards and forwards, giving the cog the nearly the same motion, as when a sole by the hands of a man, is runn'd. The lower end of this axle which is made to rise or fall at pleasure receives the smooth of the cog the similar to the grasp of a man, the smooth is located to the shaft by small iron rods and screw tips, a sweep of the cog determines the length of the frame timbers in front of the axle, which is turned into a bolster resting on the axle of the four wheels and rises as high as to make the frame perfectly level, these wheels are to pass under the frame in turning the machine. The length of the axle corresponds with the width of the former, bounds and tongue similar to those of a wagon, is attached to the axle, and horses or oxen are worked in the usual way. In the hub of the machinery wheel is a hole for the admission of oil, the under part of the axle is made of iron and is supported by a brass extending from the right to the frame - a seat may be found in this space for the driver with a gunstock and apparatus for sharpening of the blades as moving with the machine, the driver should commence on the outer edge of the field and draw round gradually approaching the center, having a full clearance for the machine after the first round. By altering the frame of this machine so as to move the horses inside of the frame, small gear may be used with it, the gear of this machine may be many and shall be regulated by the movement of the ground under the machine, if it be desired that the blades shall cut the grass inches at the extreme edge, it should move an evolution while the ground wheels pass through that space and so on by any number of inches to be desired.

What I claim as my invention and which I desire to secure by Letters Patent in the before described machine for
